(57) CLAIM

The ornamental design of a decorative stake, as shown and described.

DESCRIPTION

FIG. 1 is a perspective view of a decorative stake with a butterfly.

FIG. 2 is a top view of a decorative stake with a butterfly.

FIG. 3 is a bottom view of a decorative stake with a butterfly.

FIG. 4 is a front view of a decorative stake with a butterfly.

FIG. 5 is a first side view of a decorative stake with a butterfly.

FIG. 6 is a back view of a decorative stake with a butterfly; and,

FIG. 7 is a second side view of a decorative stake with a butterfly.

The broken lines in the drawings illustrate portions of the decorative stake for holding a light, which form no part of the claimed design.

1 Claim, 3 Drawing Sheets
